UNITED STATES PATENT OFFICE.

FREDERICK W. COLE, OF NEWTON HIGHLANDS, MASSACHUSETTS, ASSIGNOR TO THE GAMEWELL FIRE ALARM TELEGRAPH COMPANY, OF NEWTON UPPER FALLS, MASSACHUSETTS, A CORPORATION OF NEW YORK.

SIGNALING DEVICE.

1,332,322.

Specification of Letters Patent.

Patented Mar. 2, 1920.

Application filed January 12, 1917. Serial No. 141,970.

To all whom it may concern:

Be it known that I, FREDERICK W. COLE, a citizen of the United States, residing at Newton Highlands, in the county of Middlesex and State of Massachusetts, have invented an Improvement in Signaling Devices, of which the following is a specification.

In police and fire-signaling systems, it is often necessary to provide an electric signaling-device adapted to be arranged on a pole, post, or other support out of doors, where it is subjected to severe weather conditions, said device being employed to give a loud audible signal for the purpose of calling the attention of a passing officer, or for signaling street traffic. The signaling-device may be electrically connected to be controlled by the electric signaling system and arranged to give a code-signal, corresponding with a signal-box number, or it may be arranged to give an intermittent or a simple continuous signal. It has been found that the ordinary automobile horn having a vibratory diaphragm is well suited to sound an alarm for this purpose, but the device, as ordinarily constructed, is entirely unsuited to the required conditions, as it is not adapted to withstand the severe weather conditions to which it must be subjected.

This invention has for its object the construction of an electric signaling-device embodying a vibratory diaphragm which is arranged in a protecting casing and especially adapting it for use out of doors, where it is subjected to severe weather conditions, without de-arrangement or injury, and also is adapted to be attached to a post, pole, or other support. The electric signaling-device embodying my invention may be employed for other purposes.

Figure 1 is a side elevation of a signaling-device embodying this invention.

Fig. 2 is a transverse vertical section of the same.

Fig. 3 is a front view of the same.

10 represents a hollow case adapted to contain the vibratory diaphragm 11 which case has its outer face formed with a flat seat for the attachment thereto of a horn 12, and said horn having a flat seat adapted for engagement with the seat on the dia-

phragm case and to be secured thereto by screws, bolts, or other means to provide a tight weather-proof joint. Said horn is 55 bent so that when the diaphragm case is vertically disposed, as illustrated, said horn will be extended in a downward direction, see Fig. 1, thereby to prevent the rain, snow, sleet, etc., from entering it. 60

The actuating-means for the vibratory diaphragm comprises a toothed wheel 15, and a shaft 16, bearing said wheel, which shaft may be the shaft of an electric motor, and said motor is contained in a case 20, 65 which is rigidly connected with the diaphragm case and is vertically disposed. The motor terminals 22, are extended outwardly from the side wall of the motor-case. An annular flange 23, is arranged on the outside 70 of the motor-case, which, when said case is vertically disposed, occupies substantially a horizontal plane.

A pot 25 is arranged beneath the motor-case to inclose the motor terminals and thereby protect them from the weather, and said pot has a flat seat at the top, at 26, for the engagement of the flange 23, and for connection therewith by suitable bolts or screws, so that the motor-case and parts 80 connected therewith will be supported on said pot and will be rigidly connected with the pot by a tight joint. The pot has a bracket 30 formed integral with it or connected to it, which is extended laterally from 85 it and is adapted for attachment to a pole, post, or other support by means of screws or bolts, and said bracket is made hollow or provided with an interior recess 35, which is in open communication with the 90 interior of the pot, and there are provided vertical alined holes above and below said recess, which open thereto, so that the leading-in wires may pass through one or the other of said holes to the motor terminals. Said holes are threaded to receive a proper threaded pipe, through which leading-in wires will pass, and a screw-plug 38, or equivalent closure will be employed to 100 close either hole which is not being used by the pipe. This provides for leading-in wires which may be run either upward or downward, as the case may be, and a closure for the unused hole, thereby tightly closing the

pot. It will be observed that the pot with its bracket supports the motor-case and parts connected therewith, and also incloses the motor terminals, and thereby protects them from the weather.

I claim:—

1. A signaling device comprising a vibratory diaphragm, an inclosing casing therefor, actuating means including an electric motor, 10 an inclosing casing therefor, means uniting said casings, motor terminals extended from said motor casing at one end, said motor casing having an external annular flange intermediate the ends thereof, a pot having 15 an annular seat on which said flange is received, whereby said motor casing is partly in and partly out of said pot and said motor terminals are inclosed thereby, said pot having a bracket extended from it adapted to be 20 attached to a support.
2. A signaling device comprising a pot having a bracket by which it is adapted to be supported and an annular seat, an electric motor including a case having extended 25 motor terminals thereon and an external annular flange above said terminals, said motor case partially extended within said pot and said flange received on the annular seat thereof, a vibratory diaphragm arranged 30 above said pot, means supporting said diaphragm from said motor case, and means to vibrate said diaphragm by said motor.
3. A signaling-device comprising a vibratory diaphragm, actuating-means therefor 35 including an electric-motor, a case for said motor having a wall through which the motor terminals extend, a pot arranged to inclose and thereby protect the motor terminals having means adapted for supporting 40 the motor-case, and having a bracket by
- which it may be attached to a support, said bracket having a recess in open communication with the interior of the pot, and a pipe hole for the leading-in wires opening into 45 said recess.
4. A signaling-device comprising a vibratory diaphragm, actuating-means therefor including an electric-motor, a case for said motor having a wall through which the 50 motor terminals extend, a pot arranged to inclose and thereby protect the motor terminals having means adapted for supporting the motor case, and having a bracket by which it may be attached to a support, said 55 bracket having a recess in open communication with the interior of the pot, vertically-aligned pipe holes in the bracket above and below the recess, and a closure adapted to engage either hole, the other being employed for the leading-in wires.
5. A signaling-device comprising a vibratory diaphragm, actuating-means therefor including an electric-motor, a case for said diaphragm, and a case for the motor, said 65 cases being vertically disposed, and a downwardly extended horn connected with the diaphragm case, a pot arranged below the motor case adapted to inclose and thereby protect the motor terminals, and having a 70 seat to support said motor case, said pot having a bracket with an opening for the leading-in wires, adapted to be attached to a support.

In testimony whereof, I have signed my 75 name to this specification, in the presence of two subscribing witnesses.

FREDERICK W. COLE.
